UNITED STATES PATENT OFFICE.

LEALAND H. BRISTOL, OF LAWRENCEVILLE, NEW YORK.

IMPROVEMENT IN BAG-HOLDERS.

Specification forming part of Letters Patent No. **178,903**, dated June 20, 1876; application filed December 4, 1875.

To all whom it may concern:

Be it known that I, LEALAND H. BRISTOL, of Lawrenceville, St. Lawrence county, New York, have invented a new and Improved Bag-Holder, of which the following is a specification:

The invention consists in combining a slide-spout with a bench-strap and screw, and also with a wedge-shaped rest, as hereinafter described.

Figure 1 is a side elevation of my improved bag-holder. Fig. 2 is a front elevation.

Similar letters of reference indicate corresponding parts.

A is the inclined bench hinged at the lower end to the bag-stand B, and near the upper ends hinged to the legs C, to which it is also connected by the strap D, so that the height may be varied by taking up or letting out the strap. E is the spout at the upper end, under and over which the mouth of the bag is adjusted, and having hooks F, on which it is fastened, to hold the bag so that the grain shoveled into it will flow into the bag. This spout is capable of shifting up and down the

bench for long or short bags, and has a strap, G, by which, together with the clamp-screw H, to hold it in the required position. The spout rests on the bench by cleats J, which are dovetailed to the edges of the bench to hold the spout on firmly, while allowing it to shift up and down. The cleats are also to hold the bottom of the spout some distance above the bench to elevate the mouth of the bag, and under the lower end of the spout is a wedge-shaped rest, K, to graduate the bag from the spout down to the bench.

Having thus described my invention, I claim as new and desire to secure by Letters Patent—

1. The sliding spout E, combined with bench A, strap G, and screw H, as and for the purpose set forth.
2. The combination with sliding spout E, of the wedge-shaped rest K, as and for the purpose specified.

LEALAND H. BRISTOL.
